US0D1094772S

(12) **United States Design Patent** (10) Patent No.: **US D1,094,772 S**
(45) Date of Patent: ** Sep. 23, 2025

(54) **TESTING INSTRUMENT**

(71) Applicant: **LSI Medience Corporation**, Tokyo (JP)

(72) Inventors: **Yuta Moriwake**, Ehime (JP); **Masakazu Mori**, Ehime (JP); **Takahiro Misu**, Chiba (JP); **Yuji Osogawa**, Saitama (JP)

(73) Assignee: **PHC CORPORATION**, Toon (JP)

(**) Term: **15 Years**

(21) Appl. No.: **29/912,967**

(22) Filed: **Sep. 26, 2023**

(30) **Foreign Application Priority Data**

Mar. 31, 2023 (JP) ..... 2023-006708 D

(51) **LOC (15) Cl.** **24-02**

(52) **U.S. Cl.**

USPC **D24/216**; D24/232

(58) **Field of Classification Search**

USPC D24/107, 186, 232, 234, 216, 217, 224,

D24/231; D10/46, 81

CPC G01N 2035/00306; G01N 2035/00326;

G01N 33/53; G01N 33/50; G01N

33/5302

(57) **CLAIM**

The ornamental design for a testing instrument, as shown and described.

DESCRIPTION

FIG. 1 is a front perspective view of a testing instrument showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines illustrate portions of the article that form no part of the claimed design.

1 Claim, 4 Drawing Sheets
